UNITED STATES PATENT OFFICE

JOHN R. BULLIS, OF SILVER SPRING, MARYLAND

SHORING

Application filed December 30, 1930. Serial No. 505,637.

This invention relates to an improvement in shoring, and more particularly to adjustable shoring wherein two pieces of timber or struts are employed for adapting the shoring to different elevations.

The present invention resides in a clamp for the struts or timbers of the shoring for adjustably connecting them together at different elevations, and whereby various or definite adjustments may be made. The clamp consists of two plates or jaws pivotally connected together by means of parallel links for holding them in spaced relation. One of the plates is preferably connected rigidly near the top or end of one of the timbers or struts; while the other plate or jaw is provided on its inner surface with a toothed or corrugated surface for gripping a face or side of the other strut which overlaps the first strut to maintain the two struts or timbers in proper relation according to the elevation they are to assume.

The movable jaw is maintained in a rigid relation with respect to the second strut by means of a wedge interposed between the strut and a strap rigidly attached to the rigid jaw of the clamp. This wedge, therefore, performs the function of insuring the movable jaw being held against displacement and immovable until the wedge is released.

The invention consists of certain novel features of construction, and combination of parts which will be hereinafter described and set forth in the claims.

In the accompanying drawing:

Fig. 1 is a view in side elevation of the invention;

Fig. 2 is a view in edge elevation;

Fig. 3 is a transverse sectional view on line 3—3 of Fig. 1; and

Fig. 4 is a similar view on line 4—4 of Fig. 1.

The shoring in this instance is preferably composed of two strips of timber or struts 10—11, which may be of any size suitable for the purpose intended. The shoring is particularly adaptable in concrete construction for holding the necessary forms in forming the flooring or ceiling of a building, and, of course, may be utilized for various other pur-

poses such as scaffolding or where shoring might be employed.

The clamp consists of two plates or jaws 12 and 13, adapted to be used in connection with the shoring and are pivotally connected together by means of parallel links 14—14, journalled on trunnions 15 formed on the jaws 12 and 13, and held in place by means of cotter pins or other fastenings 16.

The jaws 12 and 13 are preferably made in the form of a channel or U-shaped, so that the flanges will engage the sides of the struts 10 and 11, and the jaw 12 is rigidly attached to the strut or timber 10 by means of bolts 17 passing through the flanges of the jaw and through the timber 10; while the other jaw 13 will engage three faces or sides of the opposite and overlapping strut 11 and hold it against the strut 10. This is accomplished by the movable jaw 13 automatically dropping or swinging downwardly into a plane below the stationary or fixed jaw 12. This movement of the jaw 13 is, in a measure, accomplished by the strut or timber 11 dropping under its own weight and carrying the jaw with it until the jaw has firmly gripped the strut causing it to be pressed snugly and firmly against the other strut, 10.

Now, to insure the two timbers or struts being held in this position and against any possible displacement, a strap in the form of a U has the free ends of its arms 18—18 rigidly attached by bolts or rivets 19 to the flange of the jaw 12, so that this strap encompasses the two struts and movable jaw 13. The cross member 20 of the strap, which is preferably integrally connected to the arms 18, is provided with an upwardly inclined face 21. Interposed between the movable jaw 13 and the inclined face 21 is a tapered wedge 22 which has an outwardly extending lug or projection 23 at its lower end, preventing its removal from between the jaw 13 and the cross member 20 when the clamp is in engagement with the two struts or timbers 10 and 11. When the movable jaw has been set into position for holding the struts at their proper elevation, the wedge is driven downwardly between the outer face of the jaw 13 and the face 21 of

the cross member 20, for securely locking the jaw against the strut 11, and preventing the jaw from being released from the strut until the wedge has been released or moved upwardly.

Now, in instances where the shoring has been set up for supporting formwork in the erection of a floor of a building, the adjustment of the shoring, or some of the shoring, 10 employed, may not be of the required height, and, therefore, the strut 11 must be elevated, so that it will give the needed or necessary support to the formwork. This is accomplished by means of a jack, one form of which 15 is indicated at 24 in the drawing, which may be applied to the strut 10, and by swinging the lever into engagement with the lower end of the strut 11, it will be elevated. However, before this strut 11 is elevated, the movable jaw 20 of the clamp must be released, and this is accomplished by simply disengaging the wedge sufficiently to allow the jaw 13 and strut 11 to be elevated, and upon the shore reaching the elevation required, a slight tap of a hammer 25 is applied to the movable jaw 13, whereupon it will be forced downwardly and grip the strut 11 and press it against the strut 10 and secure the two struts together. The wedge 22 is given a similar tap with a hammer for confining or forcing the jaw more firmly into engagement with the strut 11.

From the foregoing it will be apparent that this clamp may be used in connection with shoring and the two struts quickly joined together at various elevations, and in ordinary 35 adjustments a slight movement of the strut 11 with respect to the shore 10 will cause the movable jaw 13 to travel with the shore 11, causing the two shores to be securely locked 40 in overlapped relation, and to maintain these elements in this position, the wedge 22 is forced between the movable jaw 13 and strap to firmly hold the struts in place. It is to be noted, that in obtaining this clamping or 45 joining of the two struts together, that the linkage between the two jaws 12 and 13 is such that the movable jaw has a free and pivotal movement with respect to the stationary jaw 12, and the movable jaw 13 is of sufficient weight that it automatically falls below the fixed position of the stationary jaw, and, therefore, when the strut that is to be joined to the other strut is allowed to move downwardly with respect to the stationary jaw 12, 50 the movable jaw 13 will automatically travel with the strut 11, and by means of the links 14, the jaw will be constantly pulled inwardly against the moving strut and bind it more closely to the other strut until the two are 55 firmly locked together.

When it is desirable to separate the shores in obtaining another adjustment, upon releasing the wedge 22 of the clamp, the jaw 13 and strut 11 can be pulled upwardly until 60 the jaw 13 can be held away from the strut

11, and a new adjustment made. When a jack is employed, the strut 11 and jaw 13 will be automatically forced in an upward direction, and simultaneously lessening the pressure of the jaw 13 upon the strut 11, but upon obtaining this adjustment only a slight downward movement of the jaw 13 is required to firmly lock the jaw against the strut 11. The jaw will, upon discontinuing the upward pressure of the lever, automatically fall downwardly to again grip the strut 11, and by giving it a blow with a hammer, it will again securely bind the strut 11 to the strut 10, and then the wedge 22 can again be driven into position for locking the strut and jaw against movement.

A strap or guide 25 is attached to the lower end of the strut 11 and encircles the strut 10 for insuring the guiding and maintaining of the struts in proper overlapped relation.

What I claim is:—

1. A clamp, consisting of two jaws, links pivotally connecting the jaws together, a strap connected to one of the jaws and encompassing the other jaw, and means interposed between the strap and encompassed jaw for holding the jaws in engagement with a supporting member confined therebetween.

2. The combination of two members arranged in overlapped relation, a clamp consisting of two jaws, one of which is rigidly attached to one of the members, and the other jaw having engagement with the other member, links pivotally connecting the two jaws together and permitting one of the jaws to swing into engagement with a member for fastening the two members together between the jaws, a strap connected to the rigid jaw and encompassing the members and other jaw, and a wedge interposed between the strap and last mentioned jaw for holding the jaw against movement.
